(57) **CLAIM**

The ornamental design for a toll booth track component, as shown and described.

DESCRIPTION

FIG. 1 is a front-top perspective view showing a toll booth track component illustrating the toll in a down position; FIG. 2 is a rear-top perspective view of FIG. 1; FIG. 3 is a bottom-front perspective view of FIG. 1; FIG. 4 is a bottom-rear perspective view of FIG. 1; FIG. 5 is a top side view of FIG. 1; FIG. 6 is a bottom side view of FIG. 1; FIG. 7 is a front side view of FIG. 1; FIG. 8 is a rear side view of FIG. 1; FIG. 9 is a left side view of FIG. 1; FIG. 10 is a right side view of FIG. 1; FIG. 11 is a front-top perspective view showing a toll booth track component of FIG. 1 illustrating the toll in an up position;

FIG. 12 is a rear-top perspective view of FIG. 11;

FIG. 13 is a bottom-front perspective view of FIG. 11;

FIG. 14 a bottom-rear perspective view of FIG. 11;

FIG. 15 a top side view of FIG. 11;

FIG. 16 a bottom side view of FIG. 11;

FIG. 17 a front side view of FIG. 11;

FIG. 18 a rear side view of FIG. 11;

FIG. 19 a left side view of FIG. 11; and,

FIG. 20 a right side view of FIG. 11.
